UNITED STATES PATENT OFFICE.

CHESTER K. BROOKS, OF CLEVELAND, OHIO, ASSIGNOR TO THE NATIONAL MALLEABLE CASTINGS COMPANY.

FRICITION DRAFT-RIGGING.

1,163,735.

Specification of Letters Patent. Patented Dec. 14, 1915.

Application filed April 22, 1913, Serial No. 762,795. Renewed May 8, 1915. Serial No. 26,901.

To all whom it may concern:

Be it known that I, CHESTER K. BROOKS, a citizen of the United States, residing at Cleveland, Cuyahoga county, Ohio, have invented a new and useful Improvement in Friction Draft-Rigging, of which the following is a specification, reference being had to the accompanying drawings, in which—

Figure 1 is a longitudinal section of my improved draft rigging; Fig. 2 is a section on lines II—II of Fig. 1, and Fig. 3 is a section on lines III—III of Fig. 1.

My invention relates to friction draft rigging of the type shown in the co-pending application of Ernest H. Schmidt, Serial No. 734,766, filed December 3, 1912 in which the frictional elements are composed of a plurality of friction shoes and a non-compressible central friction member and in which the friction shoes are adapted to be wedged inwardly against the central member by a plurality of wedge members.

In particular, my invention has to do with the central friction member and provides a device in which the central member is free to have a certain amount of lateral play so that it will always be maintained in alignment with the draft or buffing pressures, thus decreasing the liability of its being broken. At the same time the central member is held firmly against the base of the casing and tends to remain in the center of the casing and parallel to the axis thereof.

A further object is to provide a central member which is not attached to the case which may readily be replaced when broken or worn out.

Referring to the drawings, in which I have shown a rigging of the type shown in a co-pending application of Ernest H. Schmidt, Serial No. 734,766, filed December 3, 1912, 2 indicates a case having a cylindrical bore and an enlarged portion 3 of rectangular shape preferably formed integral therewith.

Within the case 2 is a central friction member 4, which is preferably cross-shaped in cross-section. The friction member 4 has a base 5, preferably of cylindrical shape, 50 with a spherical boss 6 thereon which fits into a correspondingly shaped depression 7 in the rear follower or closed end 8 of the case 2. Strengthening webs 9 are also pro-

vided between the cross arms 10 and the base 5 of the member 4.

Between the cross arms 10 of the member 4 are located sets of friction shoes or segments 11, which are held against the central friction member 4 by the wedging rings 12, and the intermediate follower 13, as is more fully set forth in the above-mentioned application of Ernest H. Schmidt.

Around the inner portion of the central member is a compression spring 14, which abuts at its rear end against the base 5 of the central member 4 and at its forward end against the intermediate follower 13. The front follower 15 may, if desired, be made integral with the foremost wedge ring 12.

The operation of my draft rigging is similar to the operation of the rigging shown in the above-mentioned Schmidt application, except that the central friction member, not being attached to the casing, will be free to turn in the depression 7 to the extent allowed by the clearance between the rear follower and the rear face of the base 5, and bring its axis into line with the center of the line of the draft or buffing pressures when these pressures are applied out of line with the axis of the case. As the spring presses uniformly against the forward face of the base 5 when the central member 4 is located in line with the axis of the case, the central member will normally remain centered in the casing, and if it swings away from the axis the spring will return it to its axial position as soon as the unequal strains are relieved.

It will be seen therefore that the friction member, which is relatively immovable, is always maintained in the line of the buffing and draft pressures, and has the capacity of being readily detached from the other parts of the device.

It is obvious that many changes can be made in the device which I have shown and described herein without departing from my invention, since—

What I claim is:

1. In shock absorbing mechanism, a follower, a central friction member having on said follower an equalizing bearing adapted to permit the said friction member to maintain itself in alignment with the center of the line of shock, friction shoes arranged

- about the friction member, wedges for forcing the shoes against the friction member, and a spring adapted to bear at one end upon said central member and to hold it against the said follower.
2. In shock absorbing mechanism, a follower having on one side a central spherical bearing face, a central friction member having at one end a bearing surface corresponding to the bearing face on said follower, wedge actuated friction shoes bearing against said friction member, and a spring adapted to hold the said bearing surface of the friction member against said bearing face on said follower and the said friction member normally at right angles to said follower.
3. In shock absorbing mechanism, a follower having a spherical depression on one face thereof, a central friction member having a boss on one end thereof adapted to

bear in and turn in said spherical depression, friction shoes adapted to bear on said friction member, wedges for forcing said shoes against said friction member, and a spring adapted to bear at one end against said central member and to hold it against said follower.

4. In shock absorbing mechanism, a follower, a central friction member having an equalizing bearing on said follower, wedge actuated friction shoes bearing against said friction member, an enlargement extending at an angle to the body portion of said friction member and a spring adapted to bear at one end upon said enlargement and to hold it against said follower.

CHESTER K. BROOKS.
